UNITED STATES PATENT OFFICE

RALPH E. HYDE, OF CLEVELAND, OHIO, ASSIGNOR TO THE OSTER MANUFACTURING COMPANY, OF CLEVELAND, OHIO, A CORPORATION OF OHIO

DIE HEAD

Application filed July 12, 1929. Serial No. 377,776.

The present application relates, as indicated, to a die head, and more particularly to that type of die head which is provided with one or more chasers radially disposed and extending into the aperture of the head and reciprocable by means of a cam plate. The primary object of the invention is to provide a die head of the type indicated having means for automatically withdrawing the chasers from engagement with the work at a given time with respect to the amount of work which has been done. Further objects will appear as the description proceeds.

To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a front elevational view of a die head constructed in accordance with my invention; Fig. 2 is a central vertical section therethrough; and Fig. 3 is a section taken substantially upon the plane indicated by the section line 3—3 in Fig. 2 and looking in the direction of the arrows.

Referring more particularly to the drawings, it will be seen that the present device comprises a base 11 having mounted thereon or integral therewith an annular head 12. A cover plate 13 is secured to the front end of said head 12 and is formed with a plurality of projections 14 providing guide recesses 15 slidably receiving carriers 16. The projections 14 are spaced about said cover plate and are radially disposed as is clearly indicated in Figs. 1 and 2.

Referring more particularly to Fig. 2, it will be seen that each carrier 16 is provided with a longitudinal bore adapted to receive a bolt 17 to which is secured a chaser 18 through the medium of a screw connection 19. Each carrier is further provided with a transverse bore 20 for the reception of a block 21. Said block is formed with a bore

22 through which the bolt 17 passes and with a projection 23. As will be obvious, in assembling the device, the block 21 is placed in the bore 20 where after the bolt 17 is passed through the bore of the carrier 16 and through the bore 22 and the chaser 18 is secured in place. The carrier 16 is then mounted in the guide 15 and the cover plate is fastened to the head 12.

As the cover plate 13 is secured to the head 12, the projection 23 on each of the blocks 21 enters a cam groove 24 in a cam plate 25 rotatably mounted in an annular socket 26 in the head 12. A back plate 27 is likewise mounted in said socket 26, and is oscillable therein between given limits. The cam plate 25 is adjustably secured to the back plate 27, by any suitable means, in this instance a bolt 28A carried by the cam plate and having an enlarged head the edges of which bear against the under sides of a slot 28B in the back plate.

Secured to the back plate 27 and extending therefrom beyond the head 12 is a lever 28 bifurcated at its end with a slot 29. Said end is formed with a transverse bore 30 for the reception of a threaded pin 31, and adjusting nuts 32 and 33 are threaded on said pin, the nut 32 being mounted in the slot 29 and the nut 33 being adapted to abut one face of the lever 28.

A bracket 34 is secured to the head 12 and provides a pivot point 34' for an arm or handle 35 provided at its free end with a grip 36. A link 37 is pivoted at 38 to one end of the pin 31 and at its opposite end is pivoted at 39 to the arm 35. It will be seen that this arrangement provides a toggle whereby the lever 28 may be shifted. A lock nut 40 upon a pin 41 mounted in the arm 35 provides for adjustment of the pin 41 which is adapted to engage an abutment 42 on the head 12. In practice, the pin 41 is usually so adjusted that, when said pin engages the abutment 42, the pivot points 34', 39 and 38 are in dead center alignment.

At one side, the back plate 27 is cut away, as is indicated at 43 in Fig. 1, to provide a shoulder 44 into which is threaded an eye bolt 45 to which is connected one end 46 of a coil spring. The opposite end 47 of said

spring is connected to an eye bolt 48 which passes through the head 12 and is secured in place by a nut 49 abutting against a projection 50 formed on the exterior of said head.

Referring now more particularly to Fig. 2, it will be seen that the head 12 is formed to provide a cylinder 51 in which is stationarily mounted a casing 52, the bottom of which is formed with an aperture 53. As is shown in Fig. 3, said casing is formed at oppositely spaced points with a pair of slots or grooves 54. An abutment member 55 is likewise mounted in the cylinder 51 and is provided with a pair of fingers 56 slidably mounted in said grooves 54. An adjusting screw 57 passes through the aperture 53 and it is threaded into a central bore 58 in the member 55, said screw being formed with a knurled head 59 easily accessible for adjustment 20 of said screw; and intermediate its ends said screw is provided with a collar 60 adapted to engage the base of the casing 52 to limit the movement of said screw 57 under the influence of a coil spring 61 sleeved over said screw and normally held in compression between said casing 52 and said abutment 55. A stop screw 62 is adapted to be threaded into said bore 58 to lock the screw 57 in adjusted position.

Within the housing 52 there is provided a bracket 63 which provides a pivot point 64 for a bell crank lever 65. One arm 66 of said lever 65 is bifurcated to straddle the screw 57, the furcations of said arm being disposed normally in engagement with the collar 60. The other arm 67 of said lever supports a rod 68 which is mounted in a bore 69 in the head 12 and projects through an aperture 70 in the housing 52. At its upper end, the rod 68 is provided with a threaded adjusting pin 71 adapted to be secured in adjusted position by means of a lock nut 72. A bracket or projection 73 on the arm 35 extends into the path of said rod 68 and, in one position of said arm, rests upon said pin 71.

In operation, a piece of work is mounted in the aperture or cylinder 51 and is supported therein in any desired manner. The cam plate 25 having been secured to the back plate 27 in the desired adjusted position, the arm 35 is moved into the position illustrated in Fig. 1, which rotates the cam plate 25 in a clockwise direction as viewed in Fig. 1 to move the chasers 18 into operative engagement with the work. The work is now rotated and the chasers 18 cut a thread therein. As the thread is cut, the work is advanced through the chasers toward the slidable abutment 55. Eventually the work engages the abutment and forces the same toward the right as viewed in Fig. 2, compressing the spring 61, and rotating the lever 65 whereby the rod 68 is moved upwardly. Through the engagement of the pin 71 with the projection 73, such upward movement of the rod 68 ini-

tiates rotation of the arm 35 in a counter clockwise direction as viewed in Fig. 1 about its pivot 34'. Such movement of the arm 35 elevates the pivot point 39, thus moving the same out of its dead center relation with respect to the points 34' and 38. As soon as said pivot point 39 has been moved a material distance out of the dead center line, the spring 46-47 contracts to cause a sudden rotation of the back plate 27 and its connected cam plate 25 in a counter clockwise direction as viewed in Fig. 1 to retract the chasers 18.

It will be obvious, of course, that it is possible for a workman to grasp the grip 36 and manually move the arm 35 to break the toggle and permit the spring 46-47 to move the cam plate; and that this organization, even without the automatic trip device, is advantageous. It will likewise be obvious, that, in case of damage to said spring, the cam plate may be operated entirely by hand through the medium of the arm 35.

Other modes of applying the principle of the invention may be employed instead of the one explained, change being made as regards the mechanism herein disclosed, provided the means stated by any of the following claims or the equivalent of such stated means be employed.

I therefore particularly point out and distinctly claim as my invention:—

1. A device of the class described comprising a head, a radially disposed chaser reciprocably carried by said head, a cam plate mounted in said body and movable relative thereto, means connecting said chaser to said cam plate whereby movement of said plate causes reciprocation of said chaser, resilient means biasing said plate toward movement in one direction, toggle means normally resisting the bias of said resilient means, and means for breaking said toggle, said breaking means comprising a movable abutment adapted to receive the thrust of advancing work, a rod movable by said abutment, a bell crank lever actuatable by the thrust of said rod, and a second rod actuatable by said bell crank lever and bearing against one element of said toggle means.

2. In a device of the class described, a head, a chaser mounted for radial reciprocation in said head, a cam plate rotatably mounted in said head, means connecting said chaser to said plate whereby rotation of said plate in said head causes reciprocation of said chaser, a lever connected to said plate, a handle pivotally mounted on said head, a link pivotally connected to said lever and to said handle, a slidable abutment adapted to be advanced bodily by advancing work, a rod longitudinally movable at right angles to the line of advancing work bearing against said handle, and means for transmitting the thrust of said sliding abutment to cause longitudinal movement of said rod.

3. In a device of the class described, an annular head, a chaser slidably mounted on said head to extend into the aperture in said head, and automatic means for retracting said chaser comprising a cam plate connected to said chaser, a spring biasing said cam plate toward movement in one direction, toggle mechanism normally resisting the tendency of said spring, a rod reciprocably mounted in said head perpendicular to the direction of travel of work and engaging one member of said toggle mechanism, a lever having its one end in engagement with said rod, and a movable abutment disposed for movement in the direction of work being operated upon by said device and engaging said lever.

4. In a device of the class described, an annular head, the inner surface of said head defining a cylindrical work receiving aperture, a housing secured in the rear of said aperture, an abutment slidably mounted in said aperture in advance of said housing, a horizontal rod movable by said abutment and bearing reciprocably in said housing, a collar on said rod within said housing, a chaser slidably mounted on said head to extend into the aperture in said head, and automatic means for retracting said chaser comprising a cam plate connected to said chaser, a spring biasing said cam plate toward movement in one direction, toggle mechanism normally resisting the tendency of said spring, a rod reciprocably mounted in said head projecting into said housing and having one end engaging one member of said toggle mechanism, a bell crank lever having its one end in engagement with the other end of said rod, said bell crank lever having its other end in engagement with said collar.

5. In a device of the class described, an annular head, a chaser slidably mounted on said head to extend into the aperture in said head, and automatic means for retracting said chaser comprising a cam plate connected to said chaser, a spring biasing said cam plate toward movement in one direction, toggle mechanism normally resisting the tendency of said spring, a rod reciprocably mounted in said head and engaging one member of said toggle mechanism, a lever having its one end in engagement with said rod, an adjustable resiliently mounted abutment disposed for movement in the direction of work being operated upon by said device and engaging said lever.

Signed by me this 5th day of July, 1929.
RALPH E. HYDE.
